(57) **CLAIM**

The ornamental design for a vehicle fender panel, as shown and described.

DESCRIPTION

FIG. 1 is a right front perspective view of a vehicle fender panel showing our new design.

FIG. 2 is a right side view thereof.

FIG. 3 is a left side view thereof.

FIG. 4 is a front elevation view thereof.

FIG. 5 is a rear elevation view thereof.

FIG. 6 is a top plan view thereof; and,

FIG. 7 is a bottom plan view thereof.

The drawings show a vehicle fender panel for the left side of a vehicle, the vehicle fender panel for the right side of a vehicle being a mirror image thereof. The broken lines shown in the drawings represent unclaimed portions of the structure of the vehicle fender panel, and form no part of the claimed design.
